COIN RECEIVER FOR FARE BOXES
OR THE LIKE

Max L. Grant, Providence, R. I.

Application February 15, 1951, Serial No. 14,227

Term of patent 14 years

(Cl. D52—4)

To all whom it may concern:

Be it known that I, Max L. Grant, a citizen of the United States of America, residing at Providence, county of Providence, and State of Rhode Island, have invented a new, original, and ornamental Design for Coin Receiver for Fare Boxes or the Like, of which the following is a specification, reference being had to the accompanying drawings forming a part thereof, wherein:

Fig. 1 is a perspective view of a coin receiver for fare boxes, showing my new design;

Fig. 2 is a bottom view; and

Fig. 3 is a vertical transverse section from front to back.

The essential features of the design reside in the solid line portion.

I claim:

The ornamental design for a coin receiver for fare boxes or the like, substantially as shown and described.

MAX L. GRANT.
